The ornamental design for a bib, as shown and described.

DESCRIPTION

FIG. 1 is a front elevational view of a bib, showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a front perspective view thereof, shown in use.

The broken lines inside the periphery of the bib in FIGS. 1, 2 and 7 are for illustrative purposes only and form no part of the claimed subject matter. The broken lines in FIGS. 1-7 in the shape of a collar with straps are for illustrative purposes only and form no part of the claimed subject matter. The broken lines in FIG. 7 that depict the shape of a child represent environment and form no part of the claimed subject matter.
